DIE AND METHOD OF MAKING THE SAME

Edmond Haumont, Paris, France, assignor to
 United Shoe Machinery Corporation, Paterson,
 N. J., a corporation of New Jersey

Application September 18, 1934, Serial No. 744,559
 In France September 22, 1933

8 Claims. (Cl. 76—107)

This invention relates to dies and is herein illustrated as embodied in a cutting die adapted to produce shoe part blanks from sheet material such as leather.

One type of cutting die which has come into use in the production of shoe part blanks is one which comprises a blade bent to conform to the outline of a shoe part blank and having oppositely disposed cutting edges which can be used in producing either right or left blanks of similar sizes and shapes. It is an object of the present invention to provide an improved cutting die of the type referred to which will be effective in its operation and which at the same time will be economical to manufacture.

The cutting dies illustrated herein, which constitute preferred embodiments of the invention, each comprise two cutting blades having contiguous or adjacent flanges, together with means for securing the blades together. Preferably and as shown, the two blades are welded together along the flanges to form an integral construction, but they may be held together or strengthened by two plates which engage the flanges on the blades and are secured in position by fastening devices extending through the plates. Dies constructed as above outlined are well adapted to withstand the blows to which they are subjected and, at the same time, the parts which make up the dies can be readily assembled.

In another aspect, the invention relates to a method of producing cutting dies which consists in bending a flanged blade along the edges of a pattern corresponding in outline to a blank to be produced, while maintaining the flange portion of the blade in engagement with a face of the pattern and with the body portion of the blade in engagement with the edge portions of the pattern. A second blade is similarly bent about the pattern utilizing the opposite face of the pattern as a guide for the flange portion of the blade, and the two blades are then assembled with their flanged portions together to form a double-edged die. By bending the blades as above indicated about the pattern accuracy in forming the blade sections for producing closely corresponding blanks for right and left shoes, for example, is assured.

Various other features and objects of the invention will be apparent from the following detailed specification when taken in connection with the accompanying drawings and will be pointed out in the claims.

In the drawings,

Fig. 1 is a perspective view of a die illustrating one embodiment of the invention;

Fig. 2 is a side view partly in section of the die shown in Fig. 1;

Fig. 3 is a perspective view of a die illustrating another embodiment of the invention;

Fig. 4 is a perspective view of a pattern assembly which is used to form the dies;

Fig. 5 is a detailed view illustrating the step of bending one of the blade sections about the pattern assembly;

Fig. 6 is a perspective view of the step of bending the other blade section about the pattern assembly;

Fig. 7 is a side elevation partly in section of the die shown in Fig. 3; and

Fig. 8 is a perspective view partly in section of a portion of one of the blades.

The die 10 illustrated in Figs. 1 and 2 comprises a double blade formed of two symmetrical 20 blade sections 12 and 14 having oppositely disposed cutting edges 16 and inturned flanges 18 which are clamped together by core plates 20. Each of the blade sections is formed from a strip of steel such as strip 22 (Fig. 8), which is L-shaped in cross-section, one edge portion extending at right angles to the body portion as a flange 24, and the other edge portion being sharpened to form a cutting edge 26. Each of the blade sections corresponds in outline to that of a shoe 30 part blank to be produced, section 12 to a right blank and section 14 to a left blank. The blade sections 12 and 14 are positioned with their flanges 18 in engagement with each other and are clamped rigidly in position by the core plates 35 20 located within the die and having their edge portions in engagement with the flanges, the plates being held together by bolts 28, passing through aligned openings in the plates, and nuts 40 30. The flanges 18 serve to impart rigidity to the 40 double blade and stiffen it at the central portions thereof, thus preventing likelihood of the buckling of the blade under pressure applied to one or another of the cutting edges. This construction provides a reversible die which is rugged 45 but which at the same time can be readily assembled.

For producing gage marks upon blanks as they are cut from the die there are provided a plurality of stab members 32 each of which comprises a 50 shank 34 of a thickness approximately equal to the combined thickness of the flanges 18 of the blade sections and having projecting therefrom pointed portions 36 arranged to extend through holes 38 in the plates 26. When the die is as- 55

sembled the shank portion 34 is positioned between the plates and the stab member is clamped in position by the bolts 28. Preferably, and as shown, the plates 20 are provided with openings 39 centrally thereof to facilitate the removal of cut blanks from the interior of the die. If desired, a cut-out die or punches or other blank ornamenting devices, not shown, can be secured in the openings 39, or held in position between the plates 20 in the same way as the stabs 32 are held. The fact that the plates 20 are readily detachable facilitates the removal and assembly of such devices.

It is to be understood that the two blade sections 12 and 14 may be secured together by other means than the plates 20 such as by welding the blade sections together along the flanged portions thereof.

The modification illustrated in Figs. 3 and 7 comprises a die 40 having a core plate or stiffening member 41, upper and lower blade sections 42 and 44, similar in shape to blade sections 12 and 14 of the die 10, and having flanges 46 and 48 which engage opposite sides of the plate 41, the blade sections terminating in oppositely disposed cutting edges 50. In this instance the blade sections and plate are shown welded together at several points along the periphery of the die as indicated by reference characters 52.

In constructing the die shown in Fig. 1 or that illustrated in Fig. 3 use is preferably made of a pattern assembly best illustrated in Fig. 4 and which comprises a pair of plates 54 and 55 which correspond in outline to the outline of a blank to be produced. These plates are held in spaced relation by means of bolts 56 which extend through aligned openings in the plate and are secured by nuts 58, the plates being held apart by washers, one of which is shown at 60, so that the thickness of the assembly is approximately that of the body portion of a cutting blade section. By forming the pattern assembly in this manner, the necessity for a heavy plate is avoided thus making for economy since thin plates of the required shape and size can be readily produced upon a pattern grading machine.

In forming the dies the blade sections are shaped separately. For example, in producing the die 40, the cutting blade section 44 is first shaped from a strip of material such as is shown in Fig. 8 which is first bent about the pattern assembly, as illustrated in Fig. 5, with the flange 48 in engagement with the upper face of the plate 54 and the body portion of the blade in engagement with the edges of both plates. This serves to maintain the blade, as it is bent, perpendicular to the upper plate 54 with the result that the bending of the blade with its cutting edge substantially in one plane is assured, that is, the body portion of the blade will be maintained normal to the plane of the cutting edge as is necessary to produce a die which will be accurate. The bending of the blade is continued until it has been bent entirely about the pattern assembly after which the ends of the blade are welded together as indicated by reference character 62. The cutting edge is then trued up using the plate 55 as a gage thus to make sure that the edge corresponds closely to that of the pattern plate. The lower blade section is thus completed and the pattern assembly is removed therefrom. It is to be noted that in bending the blade section about corners of the pattern assembly it may be necessary to remove a portion of the flange. This is done by cutting a notch therein as shown at

64, Fig. 3. The upper blade section is similarly formed, as illustrated in Fig. 6, by bending the blade material about the pattern assembly, but in this instance the flange 46 is maintained in engagement with the lower plate 55. After the bending operation is completed the ends of the blade are welded together as indicated by reference character 66 and the blade is trued up using plate 54 as a gage.

The next step consists in removing the spacing washers 60 from the pattern assembly and reassembling the plates 54 and 55 with the blade sections 42 and 44 positioned as shown in Fig. 7 with the flanges thereof contiguous on opposite sides of the stiffening plate 41. The plates 54 and 55 are then positioned upon opposite sides of the flanges 46 and 48 and when the bolts 56 are tightened the plates will maintain the various parts in rigid position while the blade sections and stiffening plate 41 are welded together at various points along their peripheries as indicated by reference character 52. After the welding operation is completed the pattern assembly may be removed, or it may be retained as an additional stiffening means or as a support for blank marking or ornamenting devices.

In the use of a die constructed as above described the die is placed upon sheet material in a press with, for example, the left-blank cutting edge down and pressure is applied to the other edge to force the die through the material. When it is desired to produce right blanks the die is merely reversed and the operation repeated.

Having described my invention, what I claim as new and desire to secure by Letters Patent of the United States is:

1. A cutting die comprising two blade sections each of which has a body portion terminating in a cutting edge and a flange portion in engagement with the corresponding flange portion upon the other section, and means for clamping the two flange portions together.

2. A cutting die comprising a core plate, blade sections disposed upon opposite sides of the plate and having each a flange in engagement with the plate and a body portion extending substantially at right angles to the plate terminating in a cutting edge, and means for securing together the blade sections and core.

3. A cutting die comprising a blade shaped to correspond to the outline of a blank to be produced and having a flange extending laterally from the blade, a second blade shaped to correspond to the outline of a blank to be produced and having a flange positioned contiguously to the first-mentioned flange, and means for securing the flanges together.

4. A cutting die comprising a plate the outline of which corresponds approximately to the outline of a blank to be produced, a cutting blade having a body portion terminating in a cutting edge and a flanged portion extending at right angles to the body portion and in engagement with one side of the plate along the edges thereof, a second cutting blade having a body portion terminating in a cutting edge and a flange portion extending at right angles thereto located upon the plate on the opposite face thereof along the edge portions of the plate in alignment with the first-mentioned cutting blade, and means for permanently securing the blades and plate together.

5. A cutting die comprising cutting members terminating in oppositely disposed cutting edges shaped to correspond to the outline of blanks to

be produced, two core plates positioned centrally of the cutting members, and a marking member having a shank portion located between the plates and work engaging portions extending outwardly 5 of the shank portion through openings in the plates.

6. A method of producing cutting dies which consists in providing a pattern having edge portions corresponding in outline to those of blanks 10 to be produced, bending a flanged cutting blade along the edge portions of the pattern with the flange in engagement with one face of the pattern, bending a second flanged blade along the edge portions of the pattern with the flange in 15 engagement with another face of the pattern, and securing the two blades together with the flanges contiguous to each other.

7. The method of producing cutting dies which consists in providing a flanged cutting blade and 20 a pattern corresponding to the outline of a blank

to be produced, bending the blade along the pattern, utilizing the edge portions of one face of the pattern as a guide, bending a second blade along the pattern, utilizing the edge portions of the other face of the plate as a guide, assembling the two blades with their flange portions adjacent to each other, and welding the blades together. 5

8. A method of producing dies which consists in forming a pattern corresponding in outline to 10 that of a blank to be produced, bending a flanged blade along edge portions of the pattern while maintaining the flange of the blade in engagement with one face of the pattern, bending a second flanged blade along the edge portions of the 15 pattern while maintaining the flange of the second blade in engagement with the opposite face of the pattern, and permanently securing the flanges together.
